UNITED STATES PATENT OFFICE.

CLARENCE LEMUEL GUYMAN, OF TOLEDO, OHIO, ASSIGNOR TO GENERAL MOTORS CORPORATION, OF DETROIT, MICHIGAN, A CORPORATION OF DELAWARE.

HORN BUTTON.

Application filed November 2, 1922. Serial No. 593,667.

To all whom it may concern:

Be it known that I, CLARENCE L. GUYMAN, a citizen of the United States, and a resident of Toledo, in the county of Lucas 5 and State of Ohio, have invented a new and Improved Horn Button, of which the following is a full, clear, and exact description.

This invention relates to improvements in 10 horn buttons, and more particularly to devices of this character designed for use on automobiles, an object of the invention being to provide a simple and efficient construction of horn button located at the center of the steering wheel without any wiring connections leading to non-moving parts.

A further object is to provide a device of 20 the character described, which can be manufactured and sold at a reasonably low price, which can be conveniently assembled, and which will be economical in the labor cost of assemblage.

A further object is to permit the location 25 of the button on top of the wheel in connection with the solid steering post. The conventional design with the button on top of the wheel requires that the steering post be of tubing which is much more costly.

30 Also one of the features of my improvement is, that the steering post nut serves to lock the fingers of the wire into the button so that I may eventually not need to use spring tension in the wire.

35 With these and other objects in view, the invention consists in certain novel features of construction and combinations, and arrangement of parts, as will be more fully hereinafter described and pointed out in the 40 claims.

In the accompanying drawings—

Figure 1 is a view in longitudinal section illustrating my invention.

45 Figure 2 is a view in transverse section on the line 2—2, of Figure 1.

Figure 3 is a view in transverse section on the line 3—3, of Figure 1.

50 1 represents the steering column, 2 the steering post and 3 the steering wheel of an automobile. On the upper end of the post 2 a nut 4 is provided which serves to secure the steering wheel to the post and above this nut 4, and upper end of the post 2, I

locate my improved horn button 5. This button is of general inverted cup shape having in its top a hollow lug 6 receiving the upper end of a coiled spring 7 which is inserted between the nut 4 and the button 5, and functions to hold the button in its normal elevated position.

The button 5 carries a contact member 8 which comprises a spring wire preferably of steel, which is coiled intermediate its ends and located around the post 2 and normally spaced from a fixed contact 9 on the column 1. This member 8 is formed with two relatively parallel arms or rods 10, 10, which have a tension outward and at their upper free ends are formed with fingers 11, 11. The fingers 11 are positioned in sockets 70 or openings 12 in opposite sides of the button 6, and said button is provided with longitudinal tapering grooves 13 extending from the lower end of the button upwardly into the sockets or openings 12 so that when the button is pressed downwardly on the fingers 11 the latter will ride through the grooves 13 and be guided thereby into position to spring outwardly into the sockets or 75 openings 12.

The fixed contact 9 is in the form of a plug which projects through an insulating ring 14 in column 1 and the binding post 15 on said contact, is provided with a nut 16 to clamp an electric terminal 17 thereto. 80 This terminal forms a part of a wire or conductor 18 leading to the horn, and it is to be understood that the contact 8 is grounded so that when the contacts 8 and 9 are together the circuit is closed to sound the horn. 90

By reason of the construction above described, the assemblage can be conveniently made as but a single fixed contact 9 is employed, and a single opening need be provided in the column 1 to accommodate the 95 same.

The spring 7 normally holds the contacts apart, and when it is desired to sound the horn it is simply necessary to exert downward pressure on the button 5 bringing the 100 contact 8 into engagement with contact 9.

Various slight changes might be made in the general form and arrangement of parts described without departing from my invention, and hence I do not limit myself to the 105 precise details set forth, but consider my-

self at liberty to make such changes and alterations as fairly fall within the spirit and scope of the appended claims.

I claim:

- 5 1. A mechanism of the character described comprising a steering column, a steering post therein, and a steering wheel upon the upper end of said post, a fixed contact projecting through the column, a movable contact comprising a coil encircling the post and having upwardly extending and outwardly tensioned arms extending through the steering wheel, a hollow cup-shaped button coupled to the arms by reason of the 10 outward tension thereof, a spring inside said button and acting between the upper end of said steering post and the top wall of said button, said button having sockets in opposite sides thereof, and longitudinally tapered grooves extending from the lower end thereof upwardly and communicating with said sockets, and outwardly projecting fingers on the free ends of said arms the ex-
- 15

tremities of which are movable through the grooves aforesaid to guide the fingers into 25 the sockets.

2. A mechanism of the character described comprising a steering column, a steering post therein, and a steering wheel upon the upper end of said post, a fixed contact projecting through the column, a movable contact comprising a coil encircling the post and having upwardly extending and outwardly tensioned arms extending through the steering wheel, a hollow cup-shaped button coupled to the arms by reason of the outward tension thereof, a spring inside said button and acting between the upper end of said steering post and the top wall of said button, said button having sockets in opposite sides thereof, outwardly projecting fingers on the free ends of said arms, and means inside said button for guiding said fingers into said sockets as the parts are assembled.

CLARENCE LEMUEL GUYMAN.
